UNITED STATES PATENT OFFICE

2,594,965

RADIO PULSE TRANSMITTER WITH
ROTATING ANTENNA

John K. McKendry, Cambridge, Mass., assignor,
by mesne assignments, to the United States of
America as represented by the Secretary of War
Application February 19, 1945, Serial No. 578,770

3 Claims. (Cl. 250—17)

1

This invention relates to electrical systems and more particularly to electrical systems for controlling electrical driving means.

In some radio applications, use is made of a radiating element rotated about the axis of a parabolic reflector to produce a beam of energy that describes a conical path in space. The rotation of this radiating element is usually accomplished by means of a drive motor or, to use a term common to the art, "spinner motor." In some applications the energy is not radiated continuously but may be radiated in pulses, such pulses of energy usually recurring at predetermined fixed intervals of time. In some applications it is advantageous to have the number of pulses radiated per revolution of the antenna element remain constant.

One object of this invention, therefore, is to provide an electrical system for synchronizing the rotation of a radiating element with pulses fed to this radiating element from a transmitter so that the number of pulses transmitted per revolution will be constant.

Another object of the invention is to provide an electrical system for controlling an electrical driving means.

In accordance with the present invention there is provided an electrical system for moving an electrical driving means at a predetermined speed. This system comprises a source of reference voltage and an electrical driving means. A proportioning means is also included in this system for subdividing the reference voltage and applying it to the driving means. This proportioning means also serves to furnish the energy to the driving means.

Where the driving means is adapted to move a radiating means and the reference voltage is used to synchronize a transmitter which feeds the radiating means it is readily seen that such a system serves to synchronize the movement of the radiating means whereby the number of pulses transmitted per cycle of movement of the radiating means is constant.

For a better understanding of the invention together with other and further objects thereof, reference is made to the following description taken in connection with the accompanying drawings, and its scope will be pointed out in the appended claims.

The accompanying drawing shows the invention in block diagram form.

Referring now to the drawing, the block diagram shown represents one embodiment of the invention. In this drawing and the explanation

2

connected with it reference is made to specific frequencies, specific circuits and specific division ratios. It is to be understood that these references are made for ease of explanation only and are not intended nor should they be so construed as to limit the invention to the frequencies, circuits, or frequency divisions mentioned.

A multivibrator 5 is synchronized by a reference voltage of 800 cycles per second so that it operates at a frequency of 200 cycles per second or $\frac{1}{4}$ that of the reference voltage. A portion of the output of this multivibrator 5 is fed to a second multivibrator 6 to synchronize it at a frequency of 50 cycles per second, or $\frac{1}{4}$ of the input frequency or $\frac{1}{16}$ that of the reference frequency. The multivibrators used in this example could be replaced by any of the circuits well known to the art that will perform the required frequency division.

The output of the multivibrator 6 is fed through a 50 cycle filter 7. A Wien bridge filter is shown in the block as an example of a type of filter that will perform satisfactorily. The output of the filter is fed to an inverter circuit 8 as a control voltage. An example of an inverter circuit that may be used is described in connection with Fig. 170, page 265 of Engineering Electronics by Donald G. Fink, First Edition, published by McGraw-Hill Book Company, Inc. It is possible to replace the inverter circuit with a power amplifier or any other means well known to the art that will provide sufficient power to drive the spinner motor and may be synchronized by the subdivided reference frequency. The output of the inverter is applied to an electrical driving means 9, preferably a synchronous motor as shown. The shaft of this motor is mechanically coupled to a radiating element 10. A gear train 11 is shown between the spinner motor 9 and the radiating element 10. The purpose of the gear train is to cause the radiating element to rotate at a speed different from that of the spinner motor 9. The inclusion of the gear train 11 is not essential to the successful operation of the invention and may be omitted in many applications.

The same 800 cycle reference voltage that was fed to multivibrator 5 is also fed to the transmitter 14 as a synchronizing voltage. The output of the transmitter 14 is a series of radio frequency energy pulses occurring in a definite predetermined time relationship with the input synchronizing voltage. The number of pulses occurring per second is known as the pulse repetition frequency. In this example it has been assumed that one pulse is sent out from the transmitter for each cycle of input reference

voltage. Means 15 are provided for connecting the output of the transmitter 14 to the rotated radiating element 10. Suitable means 16 are provided for connecting stationary means 15 to the rotating antenna element 10.

The operation of the circuit has been described in connection with the block diagram but, in brief, it consists of applying a reference voltage to a frequency dividing means, in this case multivibrators 5 and 6, and a filter 7. This subdivided reference frequency is supplied by inverter 8 to spinner motor 9, and, therefore, drives this motor at a speed determined by the frequency of the reference voltage, the amount of the frequency division of the multivibrators 5 and 6, and the number of poles in motor 9. In the example shown the motor turns at a speed of 1500 revolutions per minute. The speed is reduced by gear train 11 so that radiating element 10 rotates at 1200 revolutions per minute. Since the output of the transmitter is one pulse per cycle of reference voltage or 800 pulses per second, the number of pulses per rotation of the radiating element 10 is fixed at 40 pulses per revolution.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

I claim:

1. An electrical circuit for synchronizing the pulse repetition frequency of a transmitter means with the rotation of a radiating element associated with said transmitter, said electrical circuit comprising a synchronous motor, a radiating element connected to and rotated by said synchronous motor, a means of introducing an alternating reference voltage, a transmitting means connected to said radiating element for

producing pulses of radio frequency energy for radiation by said radiating element, the pulse repetition frequency of said transmitting means being synchronized by said input reference voltage, means for subdividing the frequency of said input reference voltage, said means comprising two multivibrators and a Wien bridge filter connected in series, and an inverter means for supplying said subdivided reference voltage to said synchronous motor.

2. An electrical system for synchronizing the pulse repetition frequency of a transmitter with the rotation of a radiating means comprising a source of alternating reference voltage; means for subdividing the frequency of said reference voltage; a radiating means; an electrical means for driving said radiating means; means for applying said subdivided reference voltage to said driving means for controlling the movement of said radiating means in synchronism with said subdivided reference voltage, said applying means also being the source of energy for said driving means; and transmitter means connected to said source of reference voltage for generating radio frequency pulses in synchronism with said reference voltage and feeding it to said radiating means.

3. A system in accordance with claim 2 wherein said frequency subdividing means comprises a plurality of multivibrators connected in series and at least one Wien bridge filter.
